CLAIM

The ornamental design for a cosmetic package, as shown and described.

DESCRIPTION

FIG. 1 is a front perspective view of a cosmetic package showing our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The diagonal line shading in these figures represents the color green.

Broken lines shown in the figures described above show unclaimed subject matter only and form no part of the claimed design.

1 Claim, 4 Drawing Sheets
